UNITED STATES PATENT OFFICE

93,807

DESIGN FOR A DESK PEN

Robert Back, Chicago, Ill., assignor to The Wahl Company, Chicago, Ill., a corporation of Delaware

Application August 27, 1934, Serial No. 53,086

Term of patent 7 years

To all whom it may concern:

Be it known that I, ROBERT BACK, a citizen of the United States, residing at Chicago, in the county of Cook and State of Illinois, have invented a new, original, and ornamental Design for a Desk Pen, of which the following is a specification, reference being had to the accompanying drawing, forming part thereof, wherein

Fig. 1 is an elevational view of a desk pen showing my new design; and

Fig. 2 is a top or plan view of same, on a larger scale.

What I claim is:

The ornamental design for a desk pen substantially as shown.

ROBERT BACK.
